POSITIONER AND DRIVE FOR BLAST FURNACE DISTRIBUTOR

Charles Steckle and Roy L. Wingroth, Pittsburgh, Pa., assignors to United States Steel Corporation, a corporation of New Jersey

Application October 26, 1954, Serial No. 464,792

3 Claims. (Cl. 214—37)

This invention relates to an improved positioner and drive for a blast furnace distributor.

A conventional blast furnace includes a charging hopper at its upper end and a small bell and a large bell at the top and bottom respectively of this hopper. Materials to be charged to the furnace are introduced to the hopper through the small bell with the large bell closed. Subsequently an accumulation of such materials is charged to the furnace through the large bell with the small bell closed. The purpose of the double-bell arrangement is to prevent escape of gases, which are collected and used for various heating purposes. It is also known to mount the small bell in a distributor which rotates on a vertical axis. When materials are introduced to the small bell, the distributor and small bell are rotated to spread the material more evenly within the hopper. The distributor commonly is supported on a system of top, bottom and side rollers and is driven by a motor through suitable pinions and gears.

An object of the present invention is to provide a positioner and drive for a distributor capable of maintaining the parts in alignment despite wear.

A further object is to provide an improved positioner and drive which includes adjustable backing means for the distributor ring gear opposite its driving pinion, said backing means holding the gear and pinion in engagement regardless of wear on the rollers and also tending to minimize such wear.

In accomplishing these and other objects of the invention, we have provided improved details of structure, a preferred form of which is shown in the accompanying drawings, in which:

Figure 1 is a central vertical section through the top of a blast furnace having the invention incorporated therein;

Figure 2 is a plan view of the positioner of my invention with associated parts shown diagrammatically;

Figure 3 is a vertical section taken along the plane of line III—III of Figure 2; and

Figure 4 is a section taken along the plane of line IV—IV of Figure 3.

Figure 1 shows somewhat diagrammatically the upper portion of a conventional blast furnace which has a wall 10. A hopper 12 extends downwardly within the upper portion of the furnace from the top of this wall. A housing 13 extends upwardly from the top of the wall, and at its upper end rotatably supports a distributor 14. A small bell 15 is located at the bottom of the distributor, where it is suspended on a tubular rod 16 and rotates with the distributor. A large bell 17 is located at the bottom of the hopper 12 where it is suspended on a rod 18 extending through the bore of the rod 16. To prevent gas leakage, the top of the housing 13 carries a stuffing box 19 which contains packing rings 20. The outside of the distributor 14 carries a cooperating gland 21 and a circumferential flange 22 which is located above said gland and carries a ring gear 23.

2

The supporting means for the distributor includes a system of rollers which are journaled in suitable bearings mounted on a fixed spider 24 surrounding the upper portion of the housing. These rollers are shown only diagrammatically, and they include six bottom rollers 25 spaced at 60° intervals, three top rollers 26 spaced at 120° intervals, and three side rollers 27 spaced at 120° intervals alternating with the top rollers. The various rollers engage the flange 22 on the distributor. The spider 24 carries a drive motor 28 and a horizontally extending drive shaft 29. A vertically extending pinion shaft 30 is journaled in bearings 31 and 32 mounted in a housing 33 which is fixed to the spider 24. The drive shaft 29 drives the pinion shaft 30 through a worm 34 and worm gear 35 situated in the lower part of the housing 33. The pinion shaft 30 carries a pinion 36 which meshes with the outside of the ring gear 23 for driving the distributor.

In accordance with our invention, a pair of spaced apart upstanding brackets 40 are bolted to the pinion housing 33. The upper ends of the brackets carry a three-sided support which includes a pair of spaced apart bars 41 extending substantially radially of the distributor 14 and a cross bar 42 connecting the outer ends of the first named bars. To rigidify this support, a tie plate 43 preferably is bolted across the top of the bars 41 and a tie bolt 44 connects their inner ends. The inner ends of the bars 41 project over the inner edge of the ring gear 23.

A bearing housing 45 is slidably mounted between the two bars 41, having guideways 46 formed on its opposite sides receiving said bars. An adjustment bolt 47 extends radially of the distributor through said bearing housing and the cross bar 42, and carries nuts 48 on its outer end. The bearing housing contains bearings in which a pair of depending backing rollers 49 are journaled for rotation on vertical axes. The rollers 49 engage the back or inner surface of the ring gear 23 opposite the place where the pinion 36 engages. The actual point of engagement of the pinion of course lies midway between the two backing rollers. The rollers 49 are brought into close engagement with the inside of the ring gear 23 by tightening the nuts 48 on the bolt 47.

The side rollers 27 are subject to wear which tends to loosen the distributor and allow the gear and pinion to disengage. Such looseness can also produce eccentricity at the stuffing box 19 and allow escape of gases around the packing 20. Once the nuts 48 are tightened, the backing rollers 49 positively hold the ring gear 23 and distributor 14 in a proper concentric position with the ring gear engaging the pinion 36. Since there is less chance for play in the parts, wear is minimized. If desired, when our backing rolls are used, one of the adjacent side rollers 27 can be dispensed with. Our arrangement of backing rollers can be installed on existing equipment with only minor structural alterations.

While we have shown and described only a single embodiment of the invention, it is apparent that modifications may arise. Therefore, we do not wish to be limited to the disclosure set forth but only by the scope of the appended claims.

We claim:

1. In a blast furnace which includes a spider fixed adjacent the upper end of the furnace, a distributor supported on said spider for rotation on a vertical axis, a ring gear carried by said distributor, a pinion meshing with the outside of said ring gear, and drive means for said pinion supported on said spider, the combination with said ring gear of a positioner comprising a support fixed with respect to said spider above said pinion and extending over said ring gear, at least one bearing carried by

said support, and a depending backing roller journaled in said bearing and engaging the inside of said ring gear opposite said pinion.

2. In a blast furnace which includes a spider fixed adjacent the top of the furnace, a distributor supported on said spider for rotation on a vertical axis, a ring gear carried by said distributor, a pinion meshing with the outside of said ring gear, and drive means for said pinion supported on said spider, the combination with said ring gear of a positioner comprising a support fixed with respect to said spider above said pinion and extending over said ring gear, at least one bearing slidably mounted in said support, a depending backing roller journaled in said bearing, and an adjusting bolt connected to said bearing and said support for positioning said roller in engagement with the inside of said ring gear opposite said pinion.

3. In a blast furnace which includes a spider fixed adjacent the top of the furnace, a distributor supported on said spider for rotation on a vertical axis, a ring gear carried by said distributor, a pinion meshing with the outside of said ring gear, and drive means for said pinion supported by said spider, the combination with said ring gear of a positioner comprising a support fixed with respect to said spider above said pinion and extending over said ring gear, a bearing housing slidably mounted in said support for movement radially of the distributor, a pair of depending backing rollers journaled in said bearing housing for rotation on vertical axes, and an adjusting bolt connected to said bearing housing and said support for positioning said rollers in engagement with the inside of said ring gear opposite said pinion.
